(57) **CLAIM**

The ornamental design for a bucket top cutting board, as shown and described.

DESCRIPTION

FIG. 1 is a top view of the bucket top cutting board showing my new design;

FIG. 2 is a bottom view of the bucket top cutting board;

FIG. 3 is a left side elevational view of the bucket top cutting board shown in FIG. 1;

FIG. 4 is a right side elevational view of the bucket top cutting board shown in FIG. 1;

FIG. 5 is a front elevational view of the bucket top cutting board as disclosed in FIG. 1;

FIG. 6 is rear elevational view of the bucket top cutting board as disclosed in FIG. 1;

FIG. 7 is a top perspective view of the bucket top cutting board;

FIG. 8 is a bottom perspective view of the bucket top cutting board;

FIG. 9 is to perspective view of the bucket top cutting board showing the bucket top and cutting knife in dashed lines; and,

FIG. 10 is a cut away top perspective view of the bucket top cutting board showing the bucket top and cutting knife in dashed lines.

The broken lines shown in the drawings are for illustrative purposes only and form no part of the claimed design.
